UNITED STATES PATENT OFFICE.

WILLIAM B. PIERCE, OF CHICAGO, ILLINOIS.

SHUTTLE FOR WRAPPING MACHINES.

Application filed April 29, 1920. Serial No. 377,493.

To all whom it may concern:

Be it known that I, WILLIAM B. PIERCE, a citizen of the United States, and a resident of the city of Chicago, in the county of Cook 5 and State of Illinois, have invented certain new and useful Improvements in a Shuttle for Wrapping Machines; and I do hereby declare that the following is a full, clear, and exact description of the same, reference 10 being had to the accompanying drawings, and to the numerals of reference marked thereon, which form a part of this specification.

This invention relates to an improved 15 shuttle for wrapping machines. In the production of tires for use on automobiles and other vehicles, the wrapping of the tire for shipment is an important item. The desired protection is best obtained by covering the 20 tire with a spiral wrapping of paper or other flexible material, and it is highly desirable that this wrapping be strong and durable. It is also desirable that it be an economical 25 wrapping which may be easily and quickly applied. The protecting wrapping is ordinarily applied by a machine having a rotatable shuttle through which the tire to be wrapped is rotated, and the wrapping is wound on the tire from supply reels which 30 are carried on the shuttle.

It is an object therefore of this invention to provide a shuttle for wrapping machines adapted to apply a spiral wrapping around an object and to introduce one or more reinforcing wrappings into said spiral wrapping during the application thereof.

It is also an object of this invention to provide an annular shuttle for a wrapping machine having a pivoted segment removable 40 therefrom and having means whereby said segment is automatically locked in position when the shuttle is rotated.

It is an important object of this invention to provide a shuttle for wrapping machines 45 having main supply reel and auxiliary sources of wrapping material supply.

It is also an important object of this invention to provide a shuttle for wrapping machines adapted to cover an object with a 50 spiral winding of wrapping material having a plurality of reinforcing cords wound therein.

Other and further important objects of the invention will be apparent from the disclosure in the specification and the accompanying drawings.

The invention (in a preferred form) is shown on the drawings and hereinafter more fully described.

On the drawings—

Fig. 1 is a vertical section through a tire-wrapping machine equipped with the shuttle of this invention.

Fig. 2 is a front elevation of the shuttle.

Fig. 3 is a slightly enlarged side elevation 65 of one of the cord reels.

Fig. 4 is a slightly enlarged section on line 4—4 of Fig. 2.

Fig. 5 is a section on line 5—5 of Fig. 4.

Fig. 6 is a side elevation of the paper folding device.

Fig. 7 is a fragmentary top plan view of a tire protected by the improved wrapping of this invention.

Fig. 8 is a section on line 8—8 of Fig. 7. 75

Fig. 9 is a slightly enlarged section on line 9—9 of Fig. 2.

Fig. 10 is a section on line 10—10 of Fig. 9.

Fig. 11 is a slightly enlarged fragmentary 80 section on line 11—11 of Fig. 2.

As shown on the drawings—

The improved shuttle of this invention is adapted to be used in a tire-wrapping machine comprising in general the frame 1, the 85 shuttle frame 2 secured thereon, the tire-supporting and driving rollers 3 which are adjustably mounted on the frame 1, and the shuttle 4 which is constructed according to the principles of this invention, and which 90 is rotated by frictional engagement with the pulley 5 on the main drive shaft 6. Bolted to the frame 1 is a standard 7 which is provided with a bracket 8 which adjustably carries the upper guide roll 9 and the overrunning follower 10, which support and guide the top portion of the tire casing 11. The bead-pressing rollers 12 act to press the beads of the tire casing inwardly in order 95 that said casing may be compressed and 100 tightly wrapped.

The shuttle 4 comprises a symmetrical metal annulus in which the segment 13 is removably pivoted or hinged. Rotatably mounted on said shuttle 4 is a wrapping material reel 13 which is adapted to have a roll 105 of paper or other wrapping removably mounted thereon. Said reel 14 is pivoted on a shaft 16 which is secured in the shuttle 4 and extends from the side face thereof. In 110 order to removably secure the roll of paper 15 on the reel 14, a sleeve 17 is engaged

around said shaft 16, and said sleeve is provided with oppositely positioned longitudinal slots in which the leaf springs 18 are engaged. Said leaf springs rest on the shaft 16 inside the sleeve 17, and said springs resiliently press the roll of paper on the reel.

5 A tension mechanism 19 is provided for properly tensioning the strip of wrapping material as it is unwound from the roll 15 10 on the reel 14.

15 From the tension mechanism the paper is led to a folder plate 23 which, as clearly shown in Fig. 6, consists of a flat plate one margin of which is turned over and down at an angle so that the edge of a piece of paper drawn therethrough is caused to be folded over in a like manner. The folded strip of paper is led around a roller 24 journaled on a bolt 25 secured at an angle in the side face 20 of the shuttle and from said roller, which creases the fold and properly positions the strip of paper, the paper leads to the tire 11 to which it is applied.

25 Means are also provided for introducing auxiliary reinforcing windings into the paper wrappings. A cord reel 26 is pivoted on a shaft secured in the side face of the shuttle 4 and is secured thereon by a nut 27. The cord 30 from said reel 26 is guided 30 through an eye 28 which is supported on a bracket 29 on the side face of the shuttle, and said cord 30 is wound over the folds of the paper wrappings, as clearly shown in Figs. 7 and 8. A cord reel 31, similar to the 35 reel 26, is mounted on the side face of the shuttle in advance of the paper reel 14 and supplies a cord 32 which is guided to the tire casing 11 through an eye 33 similar to the eye 28. Said cord is engaged under the 40 folds of the paper wrapping as shown in Figs. 7 and 8.

The removable segment 13 is pivoted in the shuttle 4 at 34 and is so constructed that when the shuttle is closed a symmetrical annulus is formed. For locking said pivoted segment 13 in position in the shuttle, a slideable bolt 35 is mounted in a recess in said segment, and said slideable bolt is normally held outwardly by the coiled spring 36 secured to the inner end of said bolt and engaged in said recess. The outer end of the slideable bolt 35 is beveled, as shown at Fig. 10, so that it easily engages in a recess in the steel plate 37 which is secured in the end of the shuttle 4 by pins 38 when the segment 13 is closed. Due to the shape of the bevel on the outer end of the bolt 35, the segment 13 cannot be removed or opened from the shuttle without manually retracting the slideable bolt 35 against the action of the spring 36.

85 Means are provided for manually retracting the slideable bolt 35 from the recess in the hardened plate 37. A handle 39 which is slideable in a slot 40 in the face of the seg-

ment 13 is secured in said bolt 35, as clearly shown in Figs. 9 and 10, and by sliding said handle in the slot the bolt 35 may be retracted and the segment 13 unlocked. A hand grip 41 is secured in the side face of the shuttle of the segment 13 adjacent the handle 39 whereby the hand of an operator may be grasped around said hand grip and the handle to conveniently retract the bolt 35 and unlock the segment.

75 As shown in Fig. 1, a stop 42 is provided on the outer end of one of the arms of the shuttle frame 2, and when opened the segment 13 may be conveniently rested on said stop.

80 The operation is as follows—

85 The segment 13 is opened by manually operating the handle 39 and thus retracting the bolt 35, and after said segment is opened the tire to be wrapped is placed in the machine, being rotatably supported on the rollers 3 and the upper portion thereof being guided by the rollers 9 and 10. The strip of paper or other wrapping material from the reel 15 is engaged on the tire, and the cords 30 and 32 are also engaged thereon respectively over and under the strip of paper.

90 The shuttle and the tire are then caused to rotate and the relative rotation thereof causes the reinforcing cords 30 and 32 and the wrapping material to be thoroughly wound on the tire, providing a protecting covering therefor. As shown in Figs. 7 and 8, said covering consists of a spirally wound 100 strip of paper which is reinforced with the cords 30 and 32 which preclude tearing of the paper wrapping due to rough handling of the tire during shipment. Since there are two of these reinforcing cords, the paper 105 will be held securely on the tire, even if one of the cords is broken in several places. When the shuttle is opened to insert the tire, the segment 13 ordinarily rests against the stop 42 on the frame 2; and consequently 110 when the shuttle is started to rotate, the segment 13 will automatically be thrown into place and locked by the spring-pressed slideable bolts 35.

115 It is often unnecessary to provide more than one auxiliary winding and the shuttle of this invention may conveniently be used for applying a single auxiliary wrapping either over or between the folds of the main wrapping.

120 I am aware that numerous details of construction may be varied through a wide range without departing from the principles of this invention, and I therefore do not purpose limiting the patent granted other- 125 wise than necessitated by the prior art.

I claim as my invention—

1. A shuttle for wrapping machines comprising an annular frame, a wrapping material reel rotatably mounted thereon, and 130

- a rotatable cord reel on the shuttle on the frame on each side of a diameter thereof which passes through the wrapping material reel.
- 5 2. A shuttle for wrapping machines comprising a frame, a paper reel thereon, and a plurality of cord reels rotatably mounted on the same side of the frame as the paper reel.
- 10 3. The combination with a wrapping machine shuttle, of means thereon containing a supply of relatively wide wrapping material, and separate means thereon containing a supply of relatively narrow wrapping material, said means being so positioned that the narrow wrapping material is wound on the object to be wrapped between the folds of the wide wrapping material when the wrapping machine is operated.
- 15 4. A shuttle for wrapping machines comprising a rotatable frame, means on said frame for carrying a strip of material to be wound around an article to be wrapped in overlapping relation, and means on the frame for applying an auxiliary winding 25 between the overlapping layers of said strip of material.
5. A shuttle for wrapping machines comprising a rotatable frame, means on said frame for applying an overlapping strip of 30 material around the article to be wrapped, means on the frame for applying an auxiliary winding under the overlapping layers of the strip of material, and a second auxiliary reel for applying an auxiliary winding 35 over said overlapping winding.

In testimony whereof I have hereunto subscribed my name in the presence of two subscribing witnesses.

WILLIAM B. PIERCE.
